UNITED STATES PATENT OFFICE.

RICHARD DREYER, OF SEA CLIFF, NEW YORK.

SPOUT FOR CANS.

No. 831,841.

Specification of Letters Patent.

Patented Sept. 25, 1906.

Application filed February 3, 1906. Serial No. 299,291.

To all whom it may concern:

Be it known that I, RICHARD DREYER, a citizen of the United States, residing at Sea Cliff, in the county of Nassau and State of New York, have invented certain new and useful Improvements in Spouts for Cans, of which the following is a specification.

This invention relates to certain improvements in the spouts for cans for which Letters Patent No. 610,737 were granted to me under date of September 13, 1898.

It was found in the practical use of the spouts referred to that the cork washers which were used for producing the tight connection between the two disks of the spout were liable to wear out after some time, so that the spout commenced to leak and could not properly serve the function for which it was intended.

The object of this invention is to obviate the disadvantage referred to and to furnish an improved spout which has all the advantages of the spout heretofore patented, but which does not require a cork washer, so that thereby a stronger and more durable spout is obtained, which is not liable to get out of order; and for this purpose the invention consists of a spout for cans the construction of which will be fully described hereinafter and the novel features of which will be finally pointed out in the claim.

In the accompanying drawings, Figure 1 is a perspective view of the upper portion of an oil-can provided with my improved spout, shown in open position for pouring out the contents of the can. Fig. 2 is a vertical longitudinal section on line 2 2, Fig. 1. Fig. 3 is a vertical transverse section on line 3 3, Fig. 2, showing the spout in closed position; and Fig. 4 is a vertical section of a modified construction of the spout.

Similar letters of reference indicate corresponding parts in the different figures of the drawings.

Referring to the drawings, A indicates the body of the oil-can or other vessel, which is provided in the usual manner with an opening a in the top, near one corner thereof.

Around the opening in the top of the can A is soldered or otherwise attached a concave portion B of sheet metal, which is provided at its circumference with a bent-up U-shaped rim b, as shown clearly in Fig. 2. The lower part of the rim is soldered to the top of the can and serves to support the flanged rim of a cup-shaped portion d, to which the lower

curved end of a nozzle d' is attached. The cup-shaped portion d is fitted into the concave portion B, its circumferential flange being tightly held in the U-shaped rim b by means of an interposed gasket e of suitable elastic material. The concave portion B, as well as the spout portion fitted over the same, are provided with openings o o', the opening o' being formed at the point of connection with the inner end of the nozzle d', so that when the nozzle-opening o' is placed in register with the opening o in the concave portion the same is in position for pouring the contents of the can or for filling the same. For protecting the spout and concave portion against dust, &c., they are covered up by a convex cap f, which extends over the nozzle at its bent portion, as shown in Figs. 1 and 2. The cap f is provided with a vent-hole v near the spout d' and concave portion B and the slide portion d with vent-holes v' v², respectively, which register with each other when the nozzle is placed in position for pouring, as shown in Fig. 2. When the nozzle is moved to an angle of ninety degrees, as shown in dotted lines in Fig. 1, the vent-holes v' v² are placed out of register, so that the atmospheric air cannot enter into the can when the spout is closed or in non-pouring position. In the closed position of the spout the openings o o' are likewise placed out of register, so that none of the contents of the can can escape in the closed position of the spout whatever be the position of the can. When the spout is in position for discharging the contents of the can, the air enters through the vent-hole v of the cap f and the vent-holes v' v² to the interior of the can and permits thereby the free outlet of the oil or other liquid through the spout, while when the can is refilled through the spout by connection with the filling apparatus the air in the can passes freely through the vent-openings v', v², and v to the atmosphere, so as to permit the free and unobstructed refilling of the can. The nozzle d' extends downwardly through the cap f and debouches into the opening o' in the rotary part d.

In place of the construction shown in Figs. 1 to 3 the modified construction shown in Fig. 4 can be used. In this the stationary portion B' and movable portion d^x are arranged on the top of the can in inverted position. The stationary portion B' is then provided with a transverse partition p, which practically forms a portion of the spout when

the same is placed in pouring position. The partition in the cap in the stationary portion B' serves as a deflector or baffle for guiding the oil from the spout into the can when filling the same. The partition is soldered to the inside of the stationary portion and made in such a shape as to fit closely to the inner surface of the same, it being practically of segmental shape, with a slight curve from its upper toward its lower edge, as shown in Fig. 4, the lower edge being on a level with the lower edge of the guide-flange b^x. In this form the nozzle d³ does not pass downwardly, as in that previously described, but communicates directly with the registering openings in the parts B' and d^x adjacent the partition p.

The pouring of the contents of the can, as well as the filling of the same, and the ingress 20 and egress of the air through the vent-openings are accomplished in the modified construction in the same manner as in the construction shown in Figs. 1 to 3.

The advantages of my improved spout for cans are, first, that the contents of the can can be readily poured out through the nozzle after placing the same in position at right angles to the side wall of the can, the vent-openings being placed in register by the motion of 25 the spout and out of register when the spout

is returned to its inward closed position on the top of the can, and, second, that by dispensing with the cork washer between the cap and the end portion of the spout the objections to this washer and the repairs required are avoided.

Having thus described my invention, I claim as new and desire to secure by Letters Patent—

A spout for oil-cans, consisting of a concave stationary portion provided with a pouring-opening, a concave movable portion fitting within said stationary portion and provided with a pouring-opening adapted to register with said first-named pouring-opening, said stationary and movable portions being provided with vent-openings which register when said pouring-openings are in register, a cap extending over said stationary and movable portions and provided with a vent-opening, and a nozzle extending through said cap and downwardly to the pouring-opening of said movable portion.

In testimony that I claim the foregoing as my invention I have signed my name in presence of two subscribing witnesses.

RICHARD DREYER.
